(57) CLAIM

The ornamental design for a cellulite wand, as shown and described.

DESCRIPTION

FIG. 1 is a side elevational view of a cellulite wand showing my new design; and,

FIG. 2 is a front elevational view thereof.

The indicia shown on the figures are for illustrative purposes only and are hereby disclaimed as forming no part of Applicant's claimed invention.

1 Claim, 1 Drawing Sheet
